UNITED STATES PATENT OFFICE.

SIDNEY STEVENS, OF MILLINOCKET, MAINE.

CHAIR FOR INFIRM PEOPLE.

1,379,943.

Specification of Letters Patent. Patented May 31, 1921.

Application filed September 21, 1920. Serial No. 411,732.

To all whom it may concern:

Be it known that I, SIDNEY STEVENS, a citizen of the United States, residing at Millinocket, county of Penobscot, State of Maine, have invented a certain new and useful Improvement in Chairs for Infirm People, of which the following is a specification, reference being had therein to the accompanying drawings.

10 The invention relates to a new and useful improvement in chairs for infirm people. The object of the invention is to provide a chair having means for automatically assisting the sitter in rising from the chair, 15 and for partially supporting him by gradually moving downward under his weight to its proper position for sitting when he changes from a standing to a sitting posture.

15 The invention consists in providing a 20 vertically movable seat with means under the control of the sitter which when he desires to rise may be rendered operative to move slowly upward and assist him in rising into a standing posture, and which 25 when he desires to sit will gradually yield under his weight to support him in a partially sitting position while the seat is moving down to the full sitting position.

30 The invention will be fully understood 35 from the following description when taken in connection with the accompanying drawings, and the novel features thereof will be pointed out and clearly defined in the claims at the close of this specification.

35 The invention is shown as applied to a so-called Morris type of chair, although it is to be understood as adapted for application in other types of chair.

40 In the drawings, Figure 1 is a perspective view of a chair embodying the invention, the seat being shown in its downward position as when a person is sitting in it.

45 Fig. 2 is a perspective view showing the chair with the seat in its raised position.

45 Fig. 3 is a sectional view on line 3—3 of Fig. 1.

50 Fig. 4 is a vertical sectional view through one of the legs in a line diagonally of the seat, and showing a portion of the movable seat-raising frame.

55 Fig. 5 is a sectional view on line 5—5 of Fig. 4 looking upward.

Fig. 6 is a view in elevation of the seat-raising frame.

Fig. 7 is a sectional view on line 7—7 of Fig. 1.

Fig. 8 is a vertical section through the chair from front to back.

Fig. 9 is a vertical sectional view through the cylinder showing the lock for retaining the seat in its downward position when the seat has been moved to its sitting position.

Fig. 10 is a bottom plan view of one of the separable arms showing the ring members which engage with the tubular legs. 65

Referring now to the drawings, the chair is provided with four posts 1, at the four corners, each of which consists of a hollow tube. These posts also serve as legs and are preferably tied together and braced by the four horizontal braces 2, so as to form a rigid framework.

The back 3 of the chair is preferably attached to the rear brace 2 and to the two rear posts 1, 1. The two arms 4, 4 are 75 each detachably mounted on the upper ends of two of the posts 1, 1. In order to properly position the arms, each arm is provided with two positioning rings 5, 5 secured on its under side of suitable size and spaced apart so as to engage with the tubular upper ends of the front and rear posts 1, 1. They will be held against displacement by the weights suspended from them for aiding the sitter to rise, as will be hereinafter described. 80 85

The seat comprises a base portion 6 which is preferably provided with a cushion top 7, upholstered and provided with springs or otherwise suitably cushioned in well-known manner. Preferably the base 6 and the cushion are notched at the corners to fit the posts, as shown in the drawings. Secured to the base portion 6 of the seat at its four corners are flat, vertical rods 8 which lie in vertical planes and project outward from the corners of the seat base 6 at 45° to the sides of the base, as shown in Fig. 3. These flat rods 8 engage slidably in grooved ways 9 formed in the posts 1. 95 The four vertical slide rods 8 are rigidly tied together by suitable brace and tie rods. As shown in Fig. 6 there are provided top and bottom horizontal braces 10, 11 and 100

diagonal trusses 12, 12. Any other suitable form of brace and tie may be employed, however.

Secured to the under side of each arm 4 are two hangers 13 which respectively are centrally disposed inside of the rings 5 and extend down inside of the hollow posts 1. Each hanger supports a pulley 14. A cord 15 runs over each pulley 14, one end of the cord being attached to the seat-raising frame, and the other end being attached to a weight 16. Preferably the point of attachment of each cord with the seat raising frame is at the lower end of one of the flat, vertical slide rods 8. The posts 1 are each provided with a vertical slot 17 through which the cord passes from the slide rod 8 into the post for connection with the hanger. There is preferably provided a guide pulley 18 within the post at the base of the slot 17. The combined four weights 16 should be somewhat less than the combined weight of the seat frame and seat and the person who is to use the chair, so that when the sitter desires to rise from a fully seated position, he has to press upon the floor with his feet only with sufficient energy to raise part of his own weight, and the weights 16 will furnish the rest of the power required to raise him with the seat and lift him to a standing position. The weights will normally retain the seat in elevated position when the chair is not occupied. Preferably the weight is detachable from the cord, and weights of different heft are provided so that a weight of the proper heft may be employed according to the weight of the user.

In order to aid in sitting down, a retarding means is employed to retard the descent of the seat when the user begins to seat himself and rests his weight on the seat. The retarding device which I prefer to employ is pneumatic, and as shown in the drawings is as follows: Secured to the posts 1, near their lower ends, is a base 19 in the center of which is mounted an air cylinder 20, closed at the bottom. The cylinder may be formed with a flange 35 at its lower end secured to the base 19 by screws 36. The cylinder is provided with a cover 21 which is preferably screwed to the top of the cylinder. A piston rod 22 passes loosely through a hole in the cover 21, and is connected at its lower end with a piston 23 which fits loosely in the cylinder. The upper end of the piston rod 22 is provided with a cap 24 with which it is firmly connected. The cap 24 is secured to the bottom of the seat base 6 in any suitable way, as for instance by screws. When the seat is in its elevated position, the piston 23 will be at the upper end of the cylinder.

When the user is about to sit in the chair 65 he will bend his knees slightly to allow him-

self to take a partially sitting posture on the seat and let his weight come upon the seat which will gradually descend. His weight and that of the seat will overcome the heft of the four weights 16, but the descent will be retarded by the air cushion in the cylinder. The loose fit of the piston rod through the cover 21, and the loose fit of the piston 23 within the cylinders, will allow a slow passage of the air from the cylinder past the piston and out through the cover, acting as a check to retard the descent of the seat. The weights 16 will of course rise.

When the sitter rises, the weights will act to aid the ascent as already described, and the piston will be carried up with the seat, while the air enters the cylinder around the piston rod and piston. Preferably buffers 25 are provided on both the upper and under sides of the piston. When the user is fully seated, his own weight is sufficient to retain the seat in its lowermost position, if he allows his full weight to press down on the seat. If, however, he accidentally presses his feet rather forcibly on the floor, thereby taking off a part of his weight from the seat, the downward pressure of the weights 16, if free to act, would tend to lift him even though he does not really wish to rise. In order to prevent this, I prefer to provide means to lock the seat in its downward position when the user is fully seated, and to provide means whereby the sitter can easily release the detent when he wishes to rise. It is preferable to have the locking operation accomplished automatically and to have the releasing performed at the will of the operator. The locking and releasing mechanism shown is as follows: A latch member 26 is pivoted at 27 to the under side of the piston rod cap 24, and has a tooth 28 which is adapted to engage with a shoulder, as for instance the under edge of the rim of the cover 21 of the cylinder 20. The tooth has a cam face so that when the seat descends the cam face will engage the periphery of the cover in such manner as to turn the latch on its pivot enough to allow the tooth to ride down below the cover. The latch has an arm 29, and a spring 30 is provided between the arm 29 and the cap 24 to hold the latch under tension so that as soon as the tooth passes below the cover 21, the spring will cause the tooth to snap in under the rim of the cover and the latch will thus prevent the seat from rising until the latch is released. A lever 31 is pivoted to the arm 4, or to some other part of the chair within easy reach of the sitter and this lever has suitable connection with the latch 26 so that the sitter can trip the latch by operating the lever. The connecting means shown in the drawings comprises cords 32 and 33, and

the intermediate pivoted corner turn lever 34. One end of the cord 32 is secured to the lever 31 and one end of the cord 33 is secured to the latch 26, the other ends of 5 both cords being secured to the corner turn lever 34. It is obvious that any other suitable operating means for tripping the latch may be employed.

While I have shown and described a gravity device such as a weight, as the means for furnishing the force to raise the seat and thus aid the sitter in arising, it is obvious that there are equivalents which may be employed; for instance a spring in place 15 of the weight. It is also obvious that the details of construction of the various parts may easily be varied and still be within the scope of the invention.

By the use of a chair embodying the invention an infirm person can sit down easily without having almost to fall into the chair as many aged or infirm persons sometimes do. He will not have to fall or lower himself laboriously into the chair, but will be 25 gently lowered into a comfortable sitting position. The seat will then be automatically locked until the sitter wishes to rise, and then he can release the latch and the weight or other elevating means will cause 30 the seat to help him to his feet with very little effort on his part and he will be able to conserve his strength both in sitting in and arising from the chair.

The energy which he has imparted in the act of sitting is all that is needed in helping him to arise. In arising he can easily press with his feet upon the floor with an energy which would suffice to raise, say one-fourth of his weight. The chair does the 40 rest. The total of the four weights in the posts will be somewhat less than the combined weight of the chair bottom and the sitter so that the seat will go down when the sitter rests his weight upon the seat in 45 its elevated position.

What I claim is:—

1. A chair having a seat which is movable in a straight vertical path, posts forming a part of the frame of the chair, weights having flexible connections with said seat, said flexible connections running over supports on said posts, whereby the downward pull of the weights tends to pull the seat upward and thereby to aid the sitter in rising.
2. A chair having hollow posts at the four corners thereof, a vertically movable seat, vertically movable weights within said hollow posts having flexible connection with said seat, said weights together being considerably heavier than the seat, and supports in the upper part of the posts over which the said flexible connections run, whereby the downward pull of the weights tends to pull the seat upward and thereby 65 to aid the sitter in arising.

3. A chair having hollow posts at corners thereof which form part of the chair frame, a vertically movable seat frame provided with a seat, said seat frame having at its corners vertical flat rods, said posts being 70 formed with grooves within which said rods are slidable, weights within said hollow posts, cords which are connected at one end with said weights, and at the other end with said seat frame, and supports within the 75 upper ends of the posts over which the said cords run, the said weights together being sufficient to counterbalance the weight of the seat frame and at least a part of the weight of the user of the chair, whereby the 80 downward pull of the weights will aid the sitter in arising.

4. A chair having hollow posts at corners thereof which form part of the chair frame, a vertically movable seat frame provided 85 with a seat, said seat frame having vertical flat rods at its corners, said posts being formed with grooves within which said rods are slidable, arms on each of two sides of the chair, each arm being removably mounted on two of the said posts, hangers attached to said arms and extending down into the hollow interior of said posts, a pulley on each hanger, a cord running over said pulley, one end of said cord being attached to the seat frame, and a weight attached to the other end of said cord, the downward pull of the weights being sufficient to overbalance the weight of the seat and part of the weight of the user of the 90 chair.

5. A chair having hollow posts at the four corners thereof, a vertically movable seat, vertically movable weights within said hollow posts having flexible connection with 105 said seat, said weights together being considerably heavier than the seat, and supports in the upper part of the posts over which the said flexible connections run, whereby the downward pull of the weights 110 tends to pull the seat upward and thereby to aid the sitter in arising, means for automatically locking the seat in its downward position to restrain it from yielding to the pull of the weights, and means under the 115 control of the sitter to release the detent.

6. A chair having hollow posts at the four corners thereof, a vertically movable seat, vertically movable weights within said hollow posts having flexible connection with 120 said seat, said weights together being considerably heavier than the seat, and supports in the upper part of the posts over which the said flexible connections run, whereby the downward pull of the weights 125 tends to pull the seat upward and thereby to aid the sitter in arising, a base member which forms part of the frame below the seat, a cylinder mounted on said base and having a closed lower end and an apertured 130

cover at its upper end, a piston having a loose fit in said cylinder and having a piston rod which passes loosely through the cover of the cylinder and is connected with the 5 under side of the seat, said piston and cylinder forming a pneumatic check to retard the descent of the seat from its elevated position when the user seats himself, a latch-

ing device which automatically locks the seat in its downward position when the seat 10 has descended, and means under the control of the sitter to release the latch so as to allow the elevating mechanism to become operative when he desires to arise.

In testimony whereof I affix my signature. 15
SIDNEY STEVENS.
